SUPPORT FOR SHAVING BRUSHES AND OTHER ARTICLES

Filed June 30, 1947

INVENTOR.
EDWIN A. NEUGASS.

BY
Edwin A. Neugass

ATTORNEY.

UNITED STATES PATENT OFFICE

2,523,539

SUPPORT FOR SHAVING BRUSHES AND
OTHER ARTICLES

Edwin A. Neugass, Port Chester, N. Y.

Application June 30, 1947, Serial No. 758,015

3 Claims. (Cl. 248—110)

1

This invention relates to a support for shaving brushes and other articles for holding the same in fixed position when not in use. For example, after a shaving brush is rinsed with water to cleanse its bristles free from soap or shaving cream, the bristles will not dry as readily if the brush is placed in a standing position. When a shaving brush, for example, is placed in the support comprising the invention, it can be preferably placed upright, disposing the bristles in a suspended position, causing them to dry very quickly and in so doing, increasing the life of the brush. Although brushes today are being made with non-falling bristles, the old brush in which the bristles are tarred or glued are still in use; and it is for this latter type of brush that this support can be best suited for.

The support contemplated in this invention is not limited only to brushes, since it can be adapted, with minor changes but without changing the scope of this invention, to support other articles, such as tooth-brushes, combs and etc.

It is an object of the present invention to provide a practical, efficient and economical holder or support for shaving brushes and other articles.

Another object is to construct the support from suitable flexible material and of flat sheet stock so as to provide the necessary resiliency.

Still another object of the invention is to construct the support so that it may be attached in standing position to a stationary object, although it is adapted to stand without such attachment.

An even further object of the invention is the provision of semi-circular cut-outs to form clamping and recepting means for holding articles.

A still further object of the invention resides in the provision of U-shaped members forming the major part of the support.

Other objects and advantages will be in part obvious from the annexed drawing and in part hereinafter indicated in connection therewith by the following analysis of this invention.

This invention accordingly consists in the features of construction, combination of parts and in the unique relations of the members and in the relative proportioning and disposition thereof; all as more completely outlined herein.

To enable others skilled in the art so fully to comprehend the underlying features thereof that they may embody the same by the modifications in structure and relation contemplated by this invention, a drawing depicting certain forms of the invention has been annexed as a

2

part of this disclosure, and in such drawing like characters of reference denote corresponding parts throughout all the views, of which:

Fig. 1 is a left-hand elevational side view of the device comprising the invention;

Fig. 2 is a top view of the device shown in Fig. 1;

Fig. 3 is a view similar to that of Fig. 1 except that it is of the right side;

Fig. 4 is a view similar to that of Fig. 2, showing the device in working condition and engaging the head of a brush;

Fig. 5 is an elevated left-hand side view of another modification comprising the invention, shown supporting a shaving brush;

Fig. 6 is a front top view of the device shown in Fig. 5, but is shown without the brush; and

Fig. 7 is a top sectional view of the device shown in Fig. 6, with the complete top section cut away.

Now, to more specifically describe the invention, which is not intended to be limited to the modifications shown, particular reference is made to numeral 10 which represents the preferred modification of the support comprising U-shaped members A and B substantially of the same dimensions. Numeral 15 is the arm and 16 represents the base of U-shaped portion A, while U-shaped portion B comprises arm 13 and base

14. Bases 16 and 14 of the U-shaped portions or members A and B respectively, are made to permanently and fixedly engage each other as at 17, by means known in the art, such as gluing, welding, screwing and etc., so that when an

article is inserted or pushed (for example H, representing the handle of a brush) into the space or partially oval-shaped hole formed by arcuate cut-outs 19 and 20 of arms 15 and 13 respectively, said arms 15 and 13 will apply a compound spring action upon said article, supporting it in a clamped and suspended position. As is obvious from the just-mentioned connecting means, as at 17 for example, the arms 15 and 13 are movable in a plane parallel to their re-

40 spected connected bases 16 and 14, since said arms are not connected at 18, and therefore have a tendency to center around a point or area of resiliency and flexibility, substantially above the connected bases. The preferred em-

45 bodiment, just described, is assembled for example, by placing in interlocking position, U-shaped members A and B, so that leg sections 11 and 12 are disposed at right angles to each other. Consequently from such positioning, it

50 is evident that arm 15 and base 16 are disposed

55

directly over their respective elements, namely arm 13 and base 14, in partial overlapping position. As stated before, bases 14 and 16 are attached by means old in the art, such as, gluing, welding, screwing and other suitable methods.

Numeral 25 exemplifies another modification of the support, comprising the invention, having a substantially circular cut-out 32 within which the head H of shaving brush 26 is placed with its bristles BR in suspended position. This modified support 25 has Siamese walls or legs, referred to by numerals 28, which are formed by the spaced cut-out 30, which runs from the back portion of circular cut-out 32 down to a point or hole 31 in base 27. When space 34 is cut out of top portion 29, inwardly tapering arcuate portions or arms 33 are formed in said top 29 for facilitating insertion of an article therebetween. Spaces or slits 30 and 44 both lie in the same central medial plane so as to almost completely cut the support into two parts, since both slits are continuous. This particular support 25 is made of a single flat plastic sheet and differs slightly from the other support mentioned, which comprises two complementary U-shaped portions. In the modifications mentioned, the top or arm portions are substantially parallel to the base or bases. Although support 25 is formed in one piece, limited but similar compound spring action as in the preferred modification is derived from the spaces 34 and 30, the latter of which terminates at hole 31 in base 27 and from which point said compound spring action acts upon the top arm portions 33 formed by space 34 in the top 29.

It has been found that methyl methacrylate or acrylic material having similar properties is well adapted for the purpose since the U-shaped elements may be easily formed by the application of heat. Throughout the modifications shown, legs 11, 12 and 28 are integral with their respective arms and bases.

From the foregoing description taken in connection with the accompanying drawing, it is apparent that an improved simple, practical and inexpensive device for holding shaving brushes or the like is provided. It is apparent however, that immaterial changes and modifications may be made by skilled persons without departing from the true spirit and scope of the invention as outlined in the appended claims.

Having thus described my invention, what I claim as new and desire to secure by Letters Patent is:

1. A support for shaving brushes and other articles, said support comprising an integral U-shaped yieldable element forming connecting top and base, said element having a vertical cut terminating within said base and a horizontal cut through said top forming arms, said base in consequence being common to both said arms, and said arms having inwardly tapered portions conforming into semi-circular cut-outs which form a substantial clamping means for insertion and clamping of said article.
2. A support for shaving brushes or the like, said support comprising an integral U-shaped yieldable element forming a top and bottom, and a member connecting said top and bottom, said top and said member being slotted substantially at their medial line providing two substantially equal sections, said slot extending within said bottom, the said formed sections of said top having opposed cut-outs whereby an opening is provided for reception of the article to be supported, said slotted top and member complementary with said yieldable element providing a compound spring action.
3. A support for shaving brushes and other articles, said support comprising an integral U-shaped yieldable element forming connecting top and base, said element having a vertical cut terminating within said base and a horizontal cut through said top forming arms, said base in consequence being common to both said arms, and said arms having portions conforming into semi-circular cut-outs which form a substantial clamping means for insertion and clamping of said article.

EDWIN A. NEUGASS.
